WRENCH HAVING REMOVABLE AND NESTABLE SOCKETS

Sven Ivar Natanael Hall, Norrahammar, Sweden

Application January 24, 1955, Serial No. 483,638

Claims priority, application Sweden January 25, 1954

4 Claims. (Cl. 81—121)

This invention relates to wrenches and is particularly adapted to wrenches having a swing handle.

In the use of wrenches, particularly those with swing handles, it has heretofore been necessary to provide a series of wrenches each having different sizes and types for use with different screw nuts or the like. Obviously, this is expensive and cumbersome, particularly if the wrenches are to be transported in a kit.

It is, therefore, an object of the present invention to provide a wrench, particularly of the swing handle type, adapted for cooperation with a removable part for engaging over a screw nut or the like.

Another object of the invention is to provide a wrench which is inexpensive to produce and which occupies little space when folded up.

With the foregoing and other objects in view, which will become more fully apparent as the nature of the invention is better understood, the same consists in the novel features of construction, combination and arrangement of parts as will be hereinafter more fully described, illustrated in the accompanying drawing and defined in the appended claims.

In the drawing:

Figure 1 is a side elevation of a wrench according to one embodiment of the invention;

Figure 2 is a section along the line 2—2 in Figure 1;

Figure 3 is a section along the line 3—3 in Figure 1;

Figure 4 is a side elevation of the wrench with a smaller sleeve socket and a smaller bolt head than that in Figure 1;

Figure 5 is a section along the line 5—5 in Figure 4;

Figure 6 is a section along the line 6—6 in Figure 4;

Figure 7 is a side elevation of a number of sleeve sockets usable with the wrench and nested one inside the other.

Figure 8 is a section along the line 8—8 in Figure 7;

Figure 9 is a side elevation of the wrench head and shows modified means for attaching sleeve sockets thereto, and

Figure 10 is a section along the line 10—10 in Figure 9.

In Figures 1 to 3 of the drawing, numeral 1 denotes a cylindrical wrench head, on which a swing handle 3 is mounted by means of an intermediate piece 2, so as to be rockable by means of a rivet 4. On that side of the wrench head 1 opposite the handle, three sector-shaped projections 5 are provided and engage in three corresponding recesses 6 in a sleeve socket 7. The sleeve socket 7, which is a length of a hexagonal profiled tube, engages over a bolt head 8. Numeral 9 denotes a spring, which is introduced by one end into one of the projections 5 and is secured there by means of a screw 10. The free end of the spring 9 lies partly in a radially extending and relatively deep groove 11 in a sidewall of another projection 5 of the wrench head 1. A semi-cylindrical groove 12 corresponding in location to the groove 11 and also to the diameter of the spring 9 is

2

provided in a side wall of one of the recesses 6 of the sleeve socket 7, so that when the wrench head 1 and the sleeve socket 7 are being coupled the spring 9, after being pushed into its groove 11 by relative sliding movement of the adjacent grooved side wall of the recess 6, snaps into the groove 12 so as to hold the sleeve socket 7 on the wrench head 1.

Figures 4 to 6 show the same wrench head 1 connected to a sleeve socket 13, which is smaller than the sleeve socket 7 shown in Figures 1 to 3. The sleeve socket 13 engages over a bolt head 15. In this example the same projections 5 of the wrench head also engage in recesses 14 in the smaller sleeve socket 13, one of the side walls of the recess also being provided with a groove 12' similar to the groove 12 in the larger socket 7. The same spring 9 snaps into the groove 12' to hold the socket 13 on the wrench head 1.

Figures 7 and 8 show a number of sleeve sockets of different sizes, which are loosely pushed one inside the other and which can be coupled separately or together to the wrench head 1. All the sockets are usable with the same wrench head 1 and thus all have recesses and grooves complementary to the projections 5 and to the spring 9, respectively. Numeral 7 denotes the sleeve socket illustrated in Figures 1 to 3 with its recesses 6 and numeral 13 denotes the sleeve socket shown in Figures 4 to 6 with its recesses 14.

Instead of a spring, use may also be made of a permanent magnet for the purpose of attaching the sleeve sockets to the wrench head, as shown in Figure 9. Numeral 1' indicates the wrench head and numeral 3 the handle of the wrench. Numeral 5' denotes each of three sector-shaped projections of the wrench head 1'. 16 is a permanent bar magnet, which is inserted in groove 17 in the walls of two sector-shaped projections 5'. Since the sleeve sockets are made from profiled tubes, a strong magnetic attraction between the sleeve sockets and the permanent magnet 16 and hence to the wrench head 1' is ensured.

Manipulation of the wrench is clear from the drawing. If the wrench is not in use, the entire set of sockets shown in Figures 7 and 8, can be attached to the wrench head 1 so as to provide a compact assembly.

For a hexagonal sleeve socket it is advantageous for the wrench head to have three sector-shaped projections, such as those illustrated in the drawing.

The wrench according to the invention is capable, as a result of the relatively large number of different size sockets which can be coupled to one and the same head 50 of being used for loosening or tightening a correspondingly large number of screw nuts. The wrench head and the sockets are simple and inexpensive to produce, since suitable metal rods and profiled tubes can be cut to the desired length, projections or recesses than 55 being milled in one end of each of the pieces.

What I claim is:

1. A wrench having a head which is attachable at one face to a handle and which can be coupled at an opposite face to a sleeve socket which is to be engaged over a screw nut or the like, wherein the wrench head is provided on said opposite face with a number of sector-shaped projections, and wherein the sleeve socket is in the form of a tube having an interior cross section that corresponds to exterior dimensions of a screw nut or the like which is to be turned, one end of the sleeve socket having circumferentially spaced recesses corresponding in number and location to said sector-shaped projections of the wrench head, each of said recesses having longitudinal side wall surfaces lying parallel to side wall surfaces of its associated sector-shaped projection so that said recesses embrace corresponding portions of said sector-shaped projections, whereby sleeve sockets

having different size cross sections can be coupled to one and the same wrench head.

2. A wrench as claimed in claim 1, wherein a permanent magnet is mounted on side walls of two of the sector-shaped projections, for the purpose of attaching the sleeve sockets to the wrench head.

3. A wrench as claimed in claim 1, wherein a cylindrical spring has one end mounted in one of the projections of the wrench head and has a free end portion lying partly in a relatively deep groove in the side wall of another projection of the wrench head, whereby the sleeve socket may be attached to the wrench head.

5

10

4. A wrench as claimed in claim 3, wherein that recess side wall which confronts said relatively deep groove is provided with a semicylindrical groove corresponding in diameter to the diameter of the spring.
